UNITED STATES PATENT OFFICE

2,430,155

BAG HOLDER

Kenneth T. Buttery, Kalamazoo, Mich., assignor
to Sutherland Paper Company, Kalamazoo,
Mich.

Application September 29, 1944, Serial No. 556,360

7 Claims. (Cl. 226—59)

1

This invention relates to improvements in bag holder.

The main objects of this invention are:

First, to provide a bag holder adapted to open and support a bag formed of light pliable material in open position for filling and supporting it in open position in relation to a carton or container.

Second, to provide a bag holder adapted for easy manual manipulation and well adapted for use in the packaging of foods for quick freezing processing or preserving.

Third, to provide a bag holder having the advantages set forth which may be formed of relatively light container board or container stock.

Fourth, to provide a structure having these advantages which may be collapsed for shipment or storage.

Objects pertaining to details and economies of the invention will definitely appear from the description to follow. The invention is defined in the claims.

A structure which embodies the features of the invention is clearly illustrated in the accompanying drawing, in which:

Fig. 1 is a perspective view of a preferred embodiment of my invention shown in operative relation to a bag, the bag being illustrated as formed of transparent material.

Fig. 2 is a perspective view of the bag holder as illustrated in Fig. 1 disposed in filling position on a carton or container.

Fig. 3 is an enlarged transverse section on line 3—3 of Fig. 1, one of the clamping or holder members being shown in dotted lines.

Fig. 4 is an enlarged fragmentary section on line 4—4 of Fig. 2.

Fig. 5 is a plan view of the blank of the embodiment of my invention illustrated in Figs. 1 to 4, inclusive, and Fig. 6.

Fig. 6 is a perspective view illustrating the steps of setting up the holder and details of the structure thereof.

Fig. 7 is a fragmentary perspective view of a modified form or embodiment of my invention in collapsed position and positioned within a bag to be supported.

Fig. 8 is a fragmentary perspective view of the holder in its erected position with the bag ready for introduction within a carton.

Fig. 9 is a plan view of the embodiment of my invention shown in Figs. 7 and 8.

Bag holders embodying this invention are well adapted for use in filling bags used to contain food products, the bags being positioned within cartons or containers, particularly for the quick freezing of fruits and vegetables. In many cases the output is too small to justify the expense of carton erecting and filling machines, and owing to the nature of the material it is rather difficult to place a bag of thin easily fractured material,

2

such as commonly used, within a carton and hold it open for filling or extend its walls so that it will contain the full amount of material it is designed to receive. Further, it is desirable that the fruit or vegetables be packaged with a minimum of bruising or injury. Bag holders embodying this invention enable the attainment of these results.

In the accompanying drawing 1 represents a carton having closure flaps 2 and 3 on the side walls thereof and end closure flaps 4 illustrated by dotted lines in Fig. 2. The bag or container 5 is formed of suitable waterproof material and is commonly transparent as illustrated.

In the embodiment shown in Figs. 1 to 6 my improved bag holder is formed of a blank of container board or carton material and comprises opposed side walls 25, end walls 6 and sealing flap 7 at one end of the blank which is lapped upon and secured to the end wall 6 at the opposite end of the blank. The walls and sealing flap are connected by the hinged sections 8 commonly formed by scoring. The side walls have clamping and guide members 9 hingedly connected at

10 10 to their upper edges, these members being preferably tapered at their lower ends as illustrated to facilitate the entry thereof into the end of a bag 5, see the dotted line position in Fig. 3. The end walls have spreader members 11 hingedly connected to their upper edges at 12, the hinge connection being preferably formed by scoring. These spreader members are designed or adapted to be folded inwardly between the members 9, forcing them to fully erected clamping position

20 25 as shown by full lines in Fig. 3. The members 11 are preferably transversely scored at 13 so that their end portions are inwardly offset to provide an effective engagement with the member 9.

The internal dimensions of the tubular body 40 portion of the holder are such as to fittingly receive the end of the bag when it is expanded or opened as shown in Figs. 3 and 4. After the holder has been applied to the bag the bag is introduced into the container or carton 1 designed to receive

45 it and the holder is arranged on the end of the carton, preferably between a pair of closure flaps as 2 and 3 in Fig. 2 with the other pair of closure flaps as 4 in Fig. 2 disposed within the holder as illustrated. This effectively supports the holder

50 and the bag may be filled to its capacity, the holder being released by swinging up the spreader members 11 and lifting the holder from the bag which drops into the container or, with slight pressure, may be pushed into the container. The end of the bag can then be properly closed and sealed if desired and the container closed. The package is then ready for quick freezing or shipment, as the case may be.

In the embodiment of the invention shown in 60 Figs. 7, 8 and 9 the holder is formed from a blank

comprising opposed side walls 14, the end walls 15 and the sealing flap 16 which is secured to the end wall 15 of the blank, thus forming a tubular body. The walls 14 are provided with flaps 17 at their upper ends while the walls 15 have flaps 18 at their upper ends. The walls are hingedly connected, preferably by score lines 19 and the end walls and end flaps have central vertical score lines 20 permitting the collapsing of the end walls inwardly and the consequent collapsing of the side walls toward each other as shown in Fig. 7. With the walls collapsed as shown in Fig. 7 the holder is introduced into the end of a bag 5 and the holder is erected by erecting the end walls, that is, by swinging the end wall parts to erected position as shown in Fig. 8. The flaps 18 may then be swung outwardly and when in the fully erected position shown in Fig. 8 serve to hold the holder in erected position.

The lower ends 21 of the side walls are preferably tapered, these tapered portions extending beyond the lower edges of the end walls and facilitating the insertion of the holder within a bag. With the holder inserted within a bag and erected as shown in Fig. 8 it may be introduced into a 25 carton or container and the bag filled.

The holder is released by collapsing or partially collapsing the end walls which disengages not only the end walls but the side walls from the bag permitting the holder to be lifted from the 30 carton and the bag.

I have not attempted to illustrate or describe other embodiments which I contemplate and which might be desirable for adaptation to particular styles of cartons as it is believed this disclosure will enable those skilled in the art to embody or adapt my invention as may be desired.

Having thus described my invention, what I claim as new and desire to secure by Letters Patent is:

1. A bag holder formed of an integral blank and comprising side and end walls adapted to receive the open end of a bag and to supportingly engage a carton, the side walls having bag clamping and guiding members hingedly connected to their upper edges and depending within the walls, spreader members hingedly connected to the upper edges of the end walls and swingable inwardly between the said clamping members whereby the clamping members are swung outwardly to bag extending and clamping position, said spreader members engagingly retaining said clamping members in clamping position, said holder body portion being of such dimensions and cross section as to receive certain of the closure flaps of a carton within the same with other flaps of the carton disposed on the outer side thereof.

2. A bag holder formed of an integral blank and comprising side and end walls adapted to receive the open end of a bag, the side walls having bag clamping and guiding members hingedly connected to their upper edges and depending within the walls, and spreader members hingedly connected to the upper edges of the end walls and swingable inwardly between the said clamping members whereby the clamping members are swung outwardly to bag extending and clamping position, said spreader members engagingly retaining said clamping members in clamping position.

3. A bag holder formed of an integral blank and comprising side and end walls adapted to receive the open end of a bag, the side walls having bag clamping and guiding members hingedly connected to their upper edges and depend-

ing within the walls, the lower ends of said members being downwardly tapered and projecting below the lower edges of the walls, and spreader members hingedly connected to the upper edges of the end walls and swingable inwardly between the said clamping members whereby the clamping members are swung outwardly to bag extending and clamping position.

4. A bag holder comprising a tubular body of rectangular section adapted to receive the end of a bag, one pair of opposed walls of said body having bag spreading and clamping members swingably connected to the upper edges thereof to depend within the body, and coacting members swingably connected to the upper edges of the other pair of opposed walls to be swung downwardly between said clamping members for swinging them to clamping position and to engagingly retain them in such clamping position, said body being adapted to supportingly engage the upper end of a carton and to receive certain of the closure flaps thereof.

5. A bag holder comprising a tubular body of rectangular section adapted to receive the end of a bag, one pair of opposed walls of said body having bag spreading and clamping members swingably connected thereto to depend within the body, and coacting members swingably connected to the other pair of opposed walls to be swung downwardly between said clamping members for swinging them to clamping position and to engagingly retain the clamping members in clamping position.

6. A bag holder comprising a tubular body of rectangular section adapted to receive the end of a bag, one pair of opposed walls of said body having bag spreading and clamping members swingably connected thereto to depend within the body and having downwardly tapered portions facilitating the entry thereof into a bag, and coacting members swingably connected to the other pair of opposed walls to be swung downwardly between said clamping members for swinging them to clamping position and to engagingly retain the clamping members in clamping position.

7. A bag holder formed of an integral blank and comprising a tubular body of rectangular section adapted to receive a bag within the same, one pair of opposed walls of said body having tapering bag spreading members integrally and swingably connected to the upper edges thereof to depend within the body and into a bag received within said body, and flap-like members integrally and swingably connected to the upper edges of the other pair of opposed walls to be swung downwardly within the body and over the upper edge of a bag within said body.
